CLAIM

The ornamental design for a folding kitchen island table, as shown and described.

DESCRIPTION

The design of the invention disclosed herein is useful for placing a temporary kitchen island in a kitchen that does not have a kitchen island.

There is disclosed herein a folding, kitchen island table.

FIG. 1 is a front elevation view of the design for a folding kitchen island table.

FIG. 2 is an end elevation view of the design for a folding kitchen island table.

FIG. 3 is a front elevation view of the design for a folding kitchen island table showing the drawers in the end faces in the open position.

FIG. 4 is a bottom plan view of the design for a folding kitchen island table with the legs folded.

FIG. 5 is a top plan view looking down on the top surface of the design for a folding kitchen island table; and,

FIG. 6 is a bottom perspective view of the design for a folding kitchen island table with legs extended.

The inside of the drawers is not part of the claimed design.
